UNITED STATES PATENT OFFICE.

HAROLD B. DONLEY, OF COLUMBUS, OHIO, ASSIGNOR TO THE JOHN W. BROWN MANUFACTURING COMPANY, OF COLUMBUS, OHIO, A CORPORATION OF OHIO.

DESIGN FOR A SIGNAL LAMP.

Application filed March 27, 1924. Serial No. 9,081. Term of patent 14 years.

To all whom it may concern:

Be it known that I, HAROLD B. DONLEY, a citizen of the United States, residing at Columbus, in the county of Franklin and State of Ohio, have invented a new, original, and ornamental Design for Signal Lamps, of which the following is a specification, reference being had to the accompanying drawing, forming part thereof.

Figure 1 is a front elevation of a signal lamp, showing my new design, and

Figure 2 is a side elevation of the same.

I claim:

The ornamental design for a signal lamp, as shown.

HAROLD B. DONLEY.
